EYELASH CURLER

William R. Tuttle and Charles W. Stickel, Rochester, N. Y., assignors to The Kurlash Company, Inc., Rochester, N. Y., a corporation of New York

Application November 27, 1941, Serial No. 420,713

8 Claims. (Cl. 132—32)

Among the objects of the present invention is the provision of a novel eyelash curler structure constituting an improvement over that disclosed and claimed in Patents No. 1,699,084 granted July 15, 1929, No. 2,022,697 granted December 3, 1935, and particularly No. 2,252,742 granted August 19, 1941.

In the utilization of eyelash curlers or crimpers constructed in accordance with the above identified patents, except Patent No. 2,252,742, it has been found that as the relatively movable jaw is vertically reciprocated upon the vertical arm, the vertical arm engaging portions or movable sleeves on the ends of said jaw tend to irritate the skin of the face of the user and also to catch between the sleeves and the parallel arms upon which they ride facial hair from the user's cheek causing pain and being otherwise undesirable.

One of the objects of the present invention is the provision of structure whereby the user's face is protected specifically from the deleterious action of movable sleeves by the elimination thereof so that in normal use of the device no moving parts may contact the user's face.

Another object herein is the provision of such face shielding structure which is low in material cost and which may be associated with the curler with a minimum amount of labor.

A still further object herein is the provision of a novel combination eyelash curler and shielding means therefor, which is extremely simple in construction so that said shielding means may be incorporated in curlers made in accordance with the above identified patents and which will require a minimum amount of change in said curlers for the accommodation of the new shielding structure.

Another object of the present invention lies in the provision of shielding means for an eyelash curler which will enhance the appearance of the device, and generally aid in producing a streamlined contour of certain of the parts thereof.

Another object herein lies in the provision of eyelash curler structure facilitating the assembly of the device while being manufactured.

A still further object of the invention lies in the provision of structure facilitating the replacement of a removable and resilient strip facing normally maintained within the lower jaw of the curler.

These objects and other incidental ends and advantages will more fully appear in the progress of this disclosure and be pointed out in the appended claims.

Accompanying this specification and forming a

material part of this disclosure are drawings showing two embodiments of the invention herein and wherein similar reference characters designate corresponding parts throughout the several views in which:

5 Figure 1 is a side elevational view of a first embodiment of the invention with the movable or lower jaw in the elevated or closed position thereof.

10 Figure 2 is a rear elevational view of the embodiment shown in Figure 1 as might be seen from the right side of said figure.

15 Figure 3 is a fragmentary elevational view taken similarly to Figure 2 but showing the lower jaw in the lower or open position thereof.

20 Figure 4 is a fragmentary sectional view partly in elevation, as might be seen from the plane 4—4 on Figure 5.

Figure 5 is a fragmentary sectional view as might be seen from the plane 5—5 on Figure 1.

25 Figure 6 is a horizontal sectional view, partly in elevation, as might be seen from the plane 6—6 on Figure 5.

Figure 7 is a front elevational view of an eyelash curler showing a second embodiment of the invention.

30 Figure 8 is a side elevational view of the embodiment shown in Figure 7 with the lower jaw in the lowered forward disconnected position thereof.

Figure 9 is a horizontal sectional view as might be seen from plane 9—9 on Figure 8.

35 Figure 10 is an enlarged fragmentary vertical sectional view, as seen from the plane 10—10 on Figure 7.

40 Turning now to the first embodiment of the invention illustrated in Figures 1 to 6, inclusive, the eyelash curler generally indicated by numeral 30 comprises a relatively stationary element 31 and a relatively movable element 32. The stationary element comprises juxtaposed members 15 and 16, the finger loop 17, flattened portions 15' and 16', bifurcating posts 18 and 19, and vertical and parallel arms 18' and 19'. Connecting the two upper ends of the parallel arms 18' and 19' is a curved stationary upper jaw 23.

45 The relatively movable element 32 comprises juxtaposed members 10 and 11; the finger loop 12; flattened portions 13 and 14; and an irregularly shaped link 33. The link 33 is preferably formed from a single piece of rod-like material, such as wire. The link 33 includes a horizontally disposed portion 34 having a pair of lower arms 24 and 25, extending generally upwardly therefrom; the upper portions of the lower arms 24

and 25 continuing into inwardly bent oppositely disposed bifurcating post clearance portions 62 and 63. The uppermost portions of the clearance portions 62 and 63 continue into the upper arms 26 and 27; while the upper ends 64 and 65 are slightly rearwardly bent at 64' and 65' (see Figure 3). The upper ends 64 and 65 are fixedly connected to the under surface of the lower movable jaw 20. The movable jaw 20 is suitably grooved or dished to have secured therewith the resilient facing 22.

The horizontal portion 34 loosely penetrates two orifices in the upper ends of the members 10 and 11, serving thereby to pivotally connect said members to the link 33. The link 33 is reinforced by means of the crossbar 28, in turn attached to the arms 26 and 27 by means of the knuckle reinforcements 28'. The flattened portions 13 and 14 are disposed between the flattened portions 15' and 16' and are pivotally interconnected therewith by means of a pin 29.

The vertical and parallel arms 18' and 19' are provided with vertically and longitudinally arranged channels 70 and 71 respectively. The channels 70 and 71 are substantially U-shaped in horizontal cross section with the upper portions thereof oppositely disposed and facing inwardly of the device 30. The lower ends 72 and 73 of the channels 70 and 71 are preferably positioned at the point where the bifurcating posts are bent to continue upwardly into the vertical and parallel arms 18' and 19'. The lower ends 73 and 74 of the channels are disposed at a point below the normal lower limit of travel of the follower elements, said lower limit being determined by the clearance portions 62 and 63 abutting the lowermost parts of the bifurcating posts 18 and 19, just above the pin 29. The upper ends 74 and 75 of the channels 70 and 71 are positioned below the lower edge 68 of the upper jaw 23 at a distance substantially less than the vertical thickness of the resilient facing when the same is in a compressed condition so that the upward movement of the movable jaw 23 is not inhibited by the upper ends of the channels abutting the follower elements.

The outer ends of the movable jaw 20 are provided with follower elements 21 which take the form of sphere terminals on the ends of the lower jaw 20. The total effective length of the lower jaw 20, that is to say, the intersphere distance is substantially equal to or slightly less than the distance between the innermost surfaces of the channels 70 and 71 when the arms 18' and 19' are positioned through interconnection thereof by the upper jaw 23. The outer ends of the stationary jaw 23 are affixed to the upper ends of the parallel arms 18' and 19', the inner and opposite portions of the upper ends of said arms being flattened thereto to receive the ends of the stationary jaw. Attachment of the ends of the jaw to the ends of the arms may be made in any suitable manner, as, for example, by spot welding or preferably by riveting the parts together by means of integral rivets extruded from the upper ends of the arms at the time the same are flattened preparatory to the connection thereto of the ends of the stationary jaw.

The movable jaw 20 may be of rigid construction, in which event the jaw is positioned so that the follower elements 21 are disposed within the channels 70 and 71 prior to the connection of the stationary jaw 23 to the upper ends of the vertical and parallel arms 18' and 19'. On the other hand, the lower jaw 20 may be composed

5 of material having a slight degree of resiliency so that the spheres on the ends thereof may be sprung slightly toward each other and the lower jaw snapped into place within the channels 70 and 71.

10 Turning now to the second embodiment of the invention illustrated in Figures 7 to 10, inclusive, it is seen that the second embodiment presents many points of similarity to the first embodiment.

The principal difference between the two embodiments lies in the provision in the second embodiment of means to permit the simple disengagement of the follower elements 121 from the channels 170 and 171. This is accomplished by the provision of forwardly extending channel entrances 176 and 177. Throughout the ordinary range of vertical reciprocation of the movable jaw 120, the jaw is confined to its usual path 15 of travel by the follower elements 121 riding in the channels 170 and 171 from the lower ends 172 and 173 to the upper ends 174 and 175. When it is desired to replace the resilient facing 122, the loops 112 and 117 are moved toward each 20 other under more than the usual manual pressure so that the facing 122 becomes considerably compressed, as best seen in Figure 10. Manual pressure in the direction of the arrow 178 will force the follower elements 121 forwardly 25 out through the entrances 176 and 177 so that the parts will take the position best seen in Figure 8. Since the lower or movable jaw 120 in this position is removed from proximity with the stationary jaw 123 which normally overlies 30 the same, the removal of worn out resilient facing 122 and the replacement thereof with a new one becomes a relatively simple matter.

35 Another advantage of the alternate construction of the second embodiment lies in the fact 40 that the lower jaw 120 may be made of rigid material and the assembly of the follower elements within the channels 170 and 171 may take place at any stage in the manufacture of the device 130, that is to say, even after the pin 129 45 is in place and the outer ends of the stationary jaw 123 are connected to the upper ends of the vertical and parallel arms 118' and 119'.

For the purpose of avoiding needless repetition 50 other parts corresponding to those of the first embodiment are given a similar reference character with a prefix of numeral "1".

55 It may be readily seen that the present improved construction permits the eyelash curling device 30 or 130 to be operated in a manner similar to the eyelash curling device previously identified. Among the advantages presented by the present invention is that the vertical and parallel arms 18', 19', and 118' and 119' may be placed directly upon the face of the user and yet as the movable jaw 20 or 120 is vertically reciprocated no moving parts will contact the face of the user to catch facial hairs or to otherwise abrade the skin.

Furthermore, by resting the vertical and parallel arms against the face of the user the entire device may be steadied and made more stationary so that the eyelashes may be more positively retained in proper position between the stationary and movable jaw as the movable jaw is closed against the stationary jaw with the eyelashes therebetween.

60 It may thus be seen that there have been discussed two embodiments of a novel eyelash curling device possessing definite advantages in the use thereof and a novel advantageous structure

which accomplishes the desirable purpose set forth hereinabove with a minimum of parts and with a minimum of cost in fabrication and installation thereof.

We claim:

1. An eyelash curling device including: a vertical arm having a channel therein; a movable jaw having a follower element thereon; said follower element being movable along said vertical arm within said channel, said arm preventing said element from contacting the face of the user when said jaw is moved during the normal operation of the device.

2. An eyelash curling device including: a vertical arm having a channel therein; a movable jaw having a follower element at an end thereof; said follower element being movable along said vertical arm within said channel, said arm preventing said element from contacting the face of the user when said jaw is moved during the normal operation of the device.

3. An eyelash curling device including: a vertical arm having a channel therein; a movable jaw having a follower element at an end thereof; said movable jaw having a predetermined length of travel along said vertical arm; said channel being greater in length than the said predetermined length of travel of the movable jaw; said arm preventing said element from contacting the face of the user when said jaw is moved during the normal operation of the device.

4. An eyelash curling device including: a vertical arm having a channel therein substantially U-shaped in horizontal cross section; a movable jaw having a follower element at an end thereof; said follower element being movable along said vertical arm within said channel, said arm preventing said element from contacting the face of the user when said jaw is moved during the normal operation of the device.

5. An eyelash curling device including: a pair of vertical arms each having a channel; a stationary jaw attached at its ends to the upper ends of said vertical arm; a movable jaw having

5 follower elements at the ends thereof, said follower elements being slidable along said vertical arms within said channels, said follower elements being thereby shielded from contact with the face of the user when said movable jaw is moved during the normal operation of the device.

6. An eyelash curling device including: a vertical arm having a channel therein and a channel entrance; a movable jaw having a follower element thereon; said follower element being movable along said vertical arm within said channel and removable from or insertable into said channel by passing said follower element through said channel entrance, said arm preventing said element from contacting the face of the user when said jaw is moved during the normal operation of the device.

7. An eyelash curling device including: a vertical arm having a channel therein and a channel entrance of substantially the same depth as the channel; a movable jaw having a follower element thereon; said follower element being movable along said vertical arm within said channel and removable from or insertable into said channel by passing said follower element through said channel entrance, said arm preventing said element from contacting the face of the user when said jaw is moved during the normal operation of the device.

8. An eyelash curling device including: a vertical arm having a channel therein and a channel entrance; a stationary jaw attached to said vertical arm; a movable jaw having a resilient facing and a follower element, said follower element being slidable along said vertical arm within said channel, said follower element being thereby shielded from contact with the face of the user when said movable jaw is moved during the normal operation of the device, said follower element being positioned for movement through said channel entrance when the resilient facing is compressed between the stationary and movable jaws.

WILLIAM R. TUTTLE.
CHARLES W. STICKEL.
